CARPET FASTENING DEVICE

Richard T. McNicholas, Los Angeles, Calif.

Application June 20, 1938, Serial No. 214,816

2 Claims. (Cl. 16—16)

My invention relates to fastening devices and more particularly to carpet fastening devices.

One of the principal objects of my invention is to provide a fastening device so constructed and arranged as to reliably anchor a carpet or the like in adjusted position over a floor or similar structure without marring, modifying or otherwise providing the surface with openings or the like wherein to secure the device or carpet thereto.

Another object of my invention is to provide a device of the above described character of a construction adapted to maintain the marginal edges of the carpet in abutting relation with the wall adjacent the floor whereby to present a neat and uniform appearance.

A further object of my invention is to provide a device of the above described character which is simple in construction, reliable in use, efficient in operation and economical in manufacture.

A special object of my invention is to provide a device of the above described character capable of maintaining the marginal edges of carpets in abutting relation with walls having arcuate shaped corners or faces.

Another special object of my invention is to provide a device of the above described character capable of being easily removed from the floor and carpet without damage to the floor, thus eliminating the usual resultant unsightly marks, apertures and the like caused by other types of fastening devices when removed from the floor.

An important object of my invention is to provide a fastening device capable of being reliably anchored to a floor surface in a pressed condition and provided with flexible means for effecting such condition regardless of the unevenness or inequalities of the floor surface.

Another important object of my invention is to provide a fastening device of bandoleer-like formation capable of being marketed in strips of considerable length for subsequent division into suitable length portions for use in anchoring carpets to floors.

Other objects and advantages will be apparent from the following description, appended claims and annexed drawings.

Referring to the drawings wherein like reference characters designate like parts throughout the several views:

Figure 1 is a perspective view of my invention, illustrating the same attached to the floor of a building or the like adjacent a wall surface and securing a section of carpet to said floor.

Figure 2 is a transverse sectional view illus-

trating my invention in connected relation with a floor, wall and section of a carpet.

Figure 3 is a fragmentary longitudinal sectional view taken on the line 3—3 of Figure 2.

Figure 4 is a top plan view of my invention, illustrating the latter in position for securing a carpet within an arcuate shaped corner of a wall.

Figure 5 is a perspective view of a modified form of my invention.

Figure 6 is a transverse sectional view of the modified form.

Figure 7 is a fragmentary longitudinal sectional view of the modified form.

Figure 8 is a bottom plan view of the modified form.

In practicing my invention, in the preferred embodiment illustrated in Figures 1 to 4 inclusive, I provide a strip 5 of flexible material, for instance canvas, muslin, burlap or the like. Said strip is fashioned with a lengthwise extending pocket 6 and with a lateral section 7 co-extending with said pocket and comprising the pair of side ends of said strip secured together throughout the length of and adjacent one side of the pocket 20 25 6 as clearly illustrated in Figure 2. The pocket is provided with a lower face coextending with the lower face of the section 7 and coacting with the latter to form a floor engaging face 8. Said pocket is of a substantially rectangular configuration in cross section and is provided with an upper carpet engaging face 9 spaced above the upper face 10 of the section 7 to form a seat 11 for accommodating the folded end of a carpet as hereinafter more fully set forth.

Encased in the pocket 6 and conglutinated with the interior walls thereof, there is positioned a plurality of blocks 14 constructed of wood, composition board, chipped paper or the like and which serve as a filler medium for the pocket. 30 35 40

Extending through said pocket and the blocks 14 are a plurality of anchoring elements 15, for instance nails, staples or the like. One of said elements extends upwardly and in a direction towards the section 7 to form an inclined sharpened 45 upper end section above the face 9 in each of the blocks for penetrating engagement with the carpet 13 adjacent the end 12 thereof as illustrated in Figure 2. The lower ends of the anchoring elements are headed for engagement 50 with the lower face 8 of the pocket. Said blocks are spaced relative to each other to form a plurality of spaced voids within the pocket.

The lower face 8 is provided with a glue or cementing material 16 of such a character that 55

after being dried it can, when desired, be moistened with water or the like to cause the lower face 8 to adhere to the surface of the floor as illustrated in the drawings. A majority of the standard linoleum materials or paste will meet these requirements and the invention is not directed to a glue or paste of this character per se.

The facings of the blocks within the pocket provide a degree of flexibility to the strip which enable workmen to fit it to any corner or curve by slitting the pocket with a knife through the spaced voids a sufficient distance to enable a bending of the strip as clearly illustrated in Figure 4. As illustrated in Figures 1 and 2 of the drawings, the anchoring elements protrude from the top face 9 and are inclined towards the wall and the section 7 is positioned in engagement with the wall as illustrated in Figure 2. When the strip has been fitted, material 16 is moistened and the device pressed firmly to the floor and reliably anchored thereto upon a drying of the material. It is suggested, but not necessary, that the floor surface be reasonably free from sand or dirt before the device is secured in place. The flexibility obtained by the spacing of the blocks overcomes any tendency of the material 16 to fail to adhere to the floor due to the unevenness or inequalities in the floor surface or any foreign particles overlooked when applying the device thereto. When the strip has thus been secured to the floor the carpet 13 is turned under or folded to form the end 12 in the regular manner and said carpet is pressed downwardly over the protruding end of the anchoring elements 15. The folded end is seated within the seat 11. When the carpet is thus positioned it can be stretched and fastened on the opposite end to a similar device adjacent the opposite wall of the room in the same manner. Due to the inclination of the anchoring elements the carpet can be stretched as much as desired without pulling loose from said elements.

From the foregoing it will be apparent that my invention eliminates the necessity of a carpet layer driving tacks into the floor to hold the carpet in place and said invention is especially advantageous where it is desired to lay carpet on concrete, tile composition, marble, iron, or a relatively hard surface. The use of my invention makes it possible to neatly lay a carpet with the edges thereof in abutting relation with the wall thereby eliminating the unsightly appearance of the usual tack heads and the like. My invention also lessens the amount of labor and time required to lay a carpet and greatly facilitates the operation required to remove a carpet for cleaning, moving or replacing. By eliminating the necessity of using tacks or similar fasteners, it precludes damage to the floor and also the necessity of drilling and plugging in instances where marble floors are to be carpeted.

My device by reason of its bandoleer-like con-

struction, giving it the needed flexibility, insures a firm and permanent grip on the surface of the floor in appressed condition and which is not obtainable by ordinary fastening devices. The carpet may be readily removed from the anchoring devices and the strip saturated with water or the like to moisten the material 16, thereby permitting the strip to be removed from the floor without leaving any marks thereon.

In the modified form illustrated in Figures 5 to 8 inclusive, a strip 20 is provided and has secured to the under face thereof a plurality of spaced blocks 21. Said blocks are each provided with the upwardly extending anchoring means or elements 22 as clearly illustrated in the drawings. The strip 20 serves to cover the upper and outer side faces of the blocks and the under face of the blocks is provided with glue or cement for securing the blocks to the surface of the floor as in the instance of the preferred embodiment. The outer faces of the blocks are inclined as at 23 and the strip 20 extends thereover. Said strip is glued or otherwise fashioned to the upper faces of the blocks. The inclination of the upper face as at 23 permits the carpet when attached over the strip to extend downwardly therefrom for engagement with the floor. The inner ends of the blocks are adapted to abut the wall as indicated in Figure 6 and the folded ends of the carpet overlie the top face of the strip 20. This modified form of my invention is especially adaptable for use in laying carpets wherein a padding is not employed as in the instance of the preferred embodiment and is especially adaptable for use in connection with temporary carpeting.

What I claim is:

1. A device of the character described, comprising, a strip of flexible material formed with a lengthwise extending pocket and a coextending side section for abutting engagement with an upright surface, said strip provided with a lower face having adhesive material thereon for securing said strip to the surface of a floor adjacent said upright surface, a filler medium within said pocket, and anchoring elements extending through said pocket and said medium above said strip for securing carpets to said strip in adjusted position over said floor.

2. A device of the character described comprising, a strip of flexible material formed with a pocket and a side section for abutting engagement with an upright surface, said pocket provided with a lower face having adhesive material thereon for securing said strip to the surface of a floor adjacent said upright surface, a plurality of spaced blocks within said pocket, and anchoring elements extending through said pocket and said blocks above said strip for securing carpets to said strip in adjusted position over said floor.

RICHARD T. McNICHOLAS.
